2 Sheets-Sheet 1

Fig. 3.

Fig. 1.

A cross-sectional diagram of a mechanical assembly, likely a valve or pump component. The diagram shows a central vertical axis with various parts labeled with numbers. At the top, a circular component is labeled 25. Below it, a rectangular component is labeled 18. To the left of the central axis, a vertical component is labeled 15. To the right, a vertical component is labeled 16. The central axis features several internal parts: a circular component labeled 19, a rectangular component labeled 20, a horizontal rod labeled 10, and a vertical rod labeled 11. The base of the assembly is labeled 14. The entire diagram is rendered in black and white with cross-hatching for shading.

PUMP FOR OIL BURNERS OR THE LIKE

Noah Walker and Eugene H. Davis, Philadelphia, Pa.

Application October 2, 1930, Serial No. 485,975

2 Claims. (Cl. 103—162)

This invention relates to a pump of the type including a plurality of plungers reciprocating within longitudinal axially offset bores in the body of a cylindrical rotor, the plungers being preferably parallel to and spaced around a circle about the rotor axis. In pumps of this type the plunger reciprocations are effected by simultaneously rotating the rotor and constraining the plunger outer ends to keep an orbit inclined with respect to a plane perpendicular to the rotor axis, the inner ends of the plungers connecting with an arcuate inlet port when receding outwardly, connecting to a discharge port when moving inwardly and sealed when at the ends of the dead center line of the orbit.

It is thought the invention will find its best application for supplying fuel oil to oil burners but I intend my pump for the other applications for which it may be adapted.

A purpose of the invention is to adapt a pump of the character indicated to deliver at constant discharge pressure, irrespective of variant rates of use of the discharging fluid.

A further purpose is to normally operate a pump of the character indicated at one speed and one length of plunger stroke giving a rate of plunger discharge more than may be needed for the intended use, using the excess to maintain the discharge pressure constant in returning it to the inlet side of the pump.

A further purpose is to spring press a rotor cylinder of the character indicated to its end casing, using a longitudinal movement against the spring at a predetermined pressure of discharge to give a throttled by-passing connection between discharge and inlet ports within the end casing.

A further purpose is to range the arcuate inlet and discharge ports respectively open to plungers moving outwardly and inwardly in an end casing of the rotor cylinder of a pump of the character indicated.

A further purpose is to provide novel and desirable mechanism for determining the orbit of the ends of the plungers of a pump of the character indicated.

A further purpose is to make the interior space at the outer end of the rotor of a pump of the character indicated, preferably including a hollow shaft mounting the rotor, a port, inlet or outlet, for all or part of the fluid operated upon by the pump.

A further purpose is to provide novel means for easily changing the strokes of the plungers of a pump of the character indicated.

Further purposes will appear in the specification and in the claims.

It has been elected to show one main form only of the invention, showing however minor modifications and selecting a main form and modifications thereof that are practical and efficient in an operation and which well illustrate the principles involved.

Figure 1 is a broken longitudinal section, illustrating structure embodying a desirable form of the invention, the section being taken upon the line 1—1 of Figure 2.

Figure 2 is a transverse section of Figure 1 taken upon the line 2—2 thereof.

Figure 3 is a fragmentary section taken upon the line 3—3 of Figure 2.

Figure 4 is a view corresponding to a portion of Figure 1 modified with respect to a detail.

Figure 5 is a fragmentary view corresponding to another portion of Figure 1 modified with respect to another detail thereof.

Like numerals refer to like parts.

Describing in illustration and not in limitation and referring to the drawings:—

In the embodiment shown in Figures 1 and 2, the rotor 6 fits inside a longitudinal hollow 7 of a stationary casing 8. The cylinder rotor is bored axially at 9 and counterbored at 10 to present a shoulder 11 to the inner face of a screw 12 which clamps the rotor to the reduced end of its operating shaft 13.

It is preferred to make the rotor adapted to a small longitudinal movement so the operating shaft 13 when longitudinally rigid with respect to the rotor is mounted with an adaptation to small longitudinal movement.

The mechanism for rotating the shaft 13 is not shown but may be an ordinary motor, the shaft of which has normally sufficient longitudinal play for the intended longitudinal movement of the rotor.

The rotor cylinder 6 is bored longitudinally at angularly spaced intervals at 14, the axes of the bores being preferably parallel to the axis of the rotor and at uniform radial distance from the rotor axis, so that the corresponding ends of the plungers 15 within the bores 14 follow one another around a common orbit about the rotor axis.

The plungers 15 reciprocate longitudinally within the bores 14 of the rotor, each plunger reciprocating once during each rotation of the rotor, one of the desirable features of the invention including the mechanism for securing this reciprocation.

A disc 16 comprising a thin flange from a shaft 17 inclined with respect to the rotor axis, presents its outer edge within lateral slots 18 of the outer end portions of the plungers, and the disc being inclined with respect to a transverse plane through the rotor axis constrains the plungers to reciprocate during each rotation through a stroke length determined by the extent of inclination of the disc.

The individual plungers are bored from their lower ends into the slots 18, and balls 19 and compressed springs 20 are inserted within the bores, which are held to place by suitable plugs 21, the balls spring pressing upwardly into the slots against the lower side of the disc.

The bores for the balls and springs 19 and 20 may desirably not extend into the slots 18 with full diameter of bore, but the opening into the slots should be large enough to permit the balls to maintain continuous resilient engagement with the disc.

It will be seen the springs 20 press the plungers longitudinally into the rotor bores 14, the disc thereby maintaining continuous contact with plungers at the upper sides of the slots and continuous contact with the balls on the lower sides of the slots.

In this way any lost motion is avoided between the disc and plungers, despite the continuous angular variations between the disc and plungers incident to the rotation of the rotor.

The center of the disc 16 should preferably lie in the extended axis of the rotor as well as in the axis of the upwardly inclined extending shaft 17.

The shaft 17 journals in a suitably long sleeve bearing 22 and is provided with a boss or downward extension 23 below the disc to receive and guide the upper end of a spring 24, this spring being compressed between the bottom of the disc and the top of the screw 12 fastening the rotor to its shaft 9.

The disc 16, boss 23 and shaft 17 may desirably be relatively integral, with the spring 24 between the disc and rotor at once providing a flexible driving connection between the disc and rotor and pressing the disc upwardly and the rotor downwardly.

The upward pressure on the bottom of the disc is supported by a ball 25 that is adjustably positioned in the sleeve 22 at the upper end of the shaft 17 by a screw 26 threading longitudinally into the upper end of the sleeve 22.

The bearing or sleeve 22 casing the inclined shaft 17 fits an inclined bore through a housing and cover member 27, the upper and somewhat reduced end of the sleeve threading externally at 28 into the housing, and the extreme end of the sleeve being provided with a wrench hold as indicated at 29.

It will be seen that the ball 25 at the axis of the inclined shaft 17 is readily positioned by the screw 26 to eliminate frictional engagement between the disc and the lower end of the sleeve so that the compressed spring coupling between the disc and rotor introduces very little additional friction.

While it is not essential to the operation of the pump for the disc and rotor to rotate as a unit or even for the disc to rotate at all, it is very desirable from the standpoint of low friction.

As illustrated in Figure 1, the outer end of the bearing for the inclined shaft is preferably provided with a cap 30 which screws over the upper end of the housing 27, preventing any escape of

oil seeping through the bearing along the shaft 17.

The portion of the casing 8 across the inner end of the rotor is provided with grooves 31 and 32, arcuate with respect to the rotor axis and at a radial distance therefrom for registering the grooves with the ends of the bores 14 of the rotor.

The grooves 31 and 32 are on opposite sides of a plane through the relatively inclined axes of the rotor and shaft 17, this being the plane of dead center bisecting the disc 16 along its line of maximum slope, the plungers 15 within the bores 14 being longitudinally stationary at the diametrically opposite points of their orbit lying in this plane.

This plane is along the line S—S of Figure 2, the casing fitting and sealing against the inner end of the rotor except at these arcuate grooves, each of which extends along an intermediate and major portion of the semi-circular space to one side of the dead center line S—S, ending sufficient distance from the line S—S to avoid any breaking of the seal when the ends of the bores 14 are crossing their dead center points. In practice this means the spacing between the groove ends should be somewhat greater than the diameter of the bores 14.

During rotation of the rotor, the plungers 15 move outward while registering with one of the grooves and inward while registering with the other groove and any reversal of the direction of rotation of the rotor reverses the direction of movement of the plungers with respect to the groove passages 31 and 32 so that either one of these grooves may be an inlet port with the other an outlet port as determined by the direction of rotation of the rotor, the inlet and outlet ports reversing to outlet and inlet ports respectively when the direction of rotation of the rotor is reversed.

The groove passages 31 and 32 are provided with suitable external connections as indicated at 33 and 34, either one of which may be inlet while the other is an outlet or an outlet while the other is an inlet according to the direction of rotation of the rotor.

In operation the rotor may be run at a uniform speed, all of the plungers drawing fuel oil for example, into the successive bores 14 during their registry with one of the grooves, as 31, and expelling it from the bores 14 when registering with the other groove, as 32.

When the discharge pressure reaches a predetermined value, determined by the strength of the spring 24, the rotor yields longitudinally, permitting a throttled by-passing of the pumping fluid across the spaces between the grooves, no longer sealed by the end of the rotor.

The construction secures substantially uniform discharge pressure as long as the rate of use of the pumping fluid is less than the combined displacement capacities of the plungers, the rotor lifting just enough to permit a by-passing return of the excess fluid beyond that used.

In the embodiment of Figures 1 and 2 the rotor shaft is shown rigidly fastened to the rotor so that the longitudinal yielding of the rotor is accompanied by a corresponding longitudinal movement of the shaft.

Obviously there is no necessity for moving the shaft and when external conditions make it inconvenient or undesirable to move the shaft, a longitudinally movable coupling is provided between the rotor and shaft, for example as illustrated in Figure 4.

In Figure 4 the shaft 13' carries a flange 35 fitting a recess 36 in the lower end of the rotor, and having offset pin and socket longitudinal slide coupling at 37 on diametrically opposite sides 5 of the flange.

The rotor as before is pressed by the spring 24 to effect an end sealing between the groove 10 passages 31 and 32 but is adapted to move against the retraction of the spring out along the pins 15 at 37 without disturbing the drive between the rotor shaft and the rotor, thereby permitting a throttled by-passing at the predetermined discharge pressure. The selected strength of the spring is such as to maintain sealing engagement 20 between the end of the rotor and its casing until the discharge pressure reaches the predetermined limit.

In Figures 1 and 2 the bearing 22 for the shaft is shown without angular adjustment with respect 25 to the axis of the rotor. While wide variation in the rate of use without any very material change in the constant pressure of discharge and with a single or variable speed of rotation of the rotor is readily obtained without change in the stroke of the plungers, it is found sometimes 30 desirable to avoid an excessive by-passing between the discharge and inlet passages.

For this purpose the casing 22 may then be provided with an angular adjustment in order 35 to accommodate the length of plunger stroke to the duty of the pump. The quantity of fluid bypassing back from the discharge to the inlet passage varies to whatever extent may be needed to give the desired quantity for use within reasonable limits.

The angular adjustment increases the range of accommodation to the pump requirement.

In this event the structure illustrated in Figure 5, may be used where the sleeve bearing 22' makes a ball and socket connection near its lower end at 40 with the housing 41, the disc 16 being adjustable to different angles, preferably without changing the position of its center, by suitable angular adjustment of the sleeve 22' along a tapered slot 42 in the upper end of the housing 41.

The upper end of the housing 41 is provided with an outer surface at 43 arcuate with respect to the center of the disc, and the outer end of the sleeve bearing 22' is provided with an arcuate washer 44 fitting the arcuate end of the housing and is adapted to be clamped to place by a nut 45, threaded on the end of the sleeve.

The cover plate or lid 46 is shown as a cap 50 threading externally upon the housing and prevents any outward seepage of discharging fluid through the bearing of the shaft 17.

Any part or all of the pumping fluid may be circulated through the interior space 47 at the outer end of the rotor and that encloses the disc 16. The projecting ends of the plungers and the spring coupling between the disc and

rotor secure an accompanying advantage of lubrication or/and cooling the interior bearings and surfaces of the mechanism or/and optionally also of using the hollow shaft of the rotor as an inlet or discharge conduit of the pump.

In Figures 2 and 3 the passages 31 and 32, of which one is shown connected by bores 48 and 49 with the upper portion of the space 47 and the other of these passages is provided with suitable throttling passages 50, 51 and 52 to 80 the hollow interior of the rotor shaft 13.

More usually a small portion only of the flow will be passed thus to the interior of the pump, for cooling and lubricating purposes, but under special conditions the entire flow may be sent 85 through the interior space 47 using the hollow shaft as either an outlet or an inlet conduit. It is then desirable to omit the throttled passages 50, 51 and 52.

Obviously by partially or wholly closing the 90 external connection 33 any desired portion of the flow may pass through the hollow shaft, inwardly or outwardly according to the direction of rotation of the rotor, the other external connection 34 being an outlet when the hollow shaft 100 is an inlet or an inlet with the hollow shaft an outlet.

In view of our invention and disclosure variations and modifications to meet individual whim or particular need will doubtless become evident 105 to others skilled in the art, to obtain all or part of the benefits of our invention without copying the structure shown, and we, therefore, claim all such in so far as they fall within the reasonable spirit and scope of our invention.

Having thus described our invention, what we 110 claim as new and desire to secure by Letters Patent is:—

1. In a mechanism of the character indicated, a cylindrical rotor having longitudinal bores offset from and substantially parallel to the rotor axis, pumping plungers in the bores, a disc diagonal to the axis of the rotor laterally entering the plungers, balls bearing against the disc on the pressure sides of the plungers, compressed 115 springs between the balls and plungers whereby the initial operating pressure of the plungers is effected through the balls.

2. In a rotary pump, a casing having a cylindrical interior, a cylindrical rotor within the casing having a plurality of bores spaced around the axis of the rotor and substantially parallel to the axis of the rotor, a hollow plunger in each bore laterally slotted at one end, a rotor disc eccentric extending into the lateral slot of each 120 plunger, a ball in each plunger in contact with the eccentric, a spring in each plunger urging the ball to place and a stop closing the end of each plunger and engaging the opposite end of each spring from that in contact with the ball. 125
